H. SORENSEN

CONSTRUCTION OF FIREPROOF BUILDINGS

Filed May 18, 1926

FIG. 1

FIG. 2

FIG. 3

Henry Sorensen
INVENTOR

UNITED STATES PATENT OFFICE.

HENRY SORENSEN, OF SAN FRANCISCO, CALIFORNIA.

CONSTRUCTION OF FIREPROOF BUILDINGS.

Application filed May 18, 1926. Serial No. 109,891.

My invention, herein, consists of a novel and simple device, by which I apply the principle of the wedge to stretch and interlock the reinforcements with the supports of the infilled structure, and while my invention may be utilized in various ways, I have described it applied to fireproof floors.

In the accompanying drawings, where similar numerals indicate similar parts;

Fig. 1 illustrates my invention before the wedging of the reinforcement, against the support of the infilled structure, has taken place.

Fig. 2 illustrates my invention after the wedging of the reinforcement, against the said support, is done.

Fig. 3 is a plan view of my invention showing the reinforcements in place, and ready to receive the infilling.

Numerals 1 designate the reinforcements. Numerals 2 designate hooks which hold reinforcements 1 to beams 3. Beams 3 support the floor, and numerals 4 are columns which, in turn, support beams 3. Numerals 5 designate wedgeshaped elongations attached to reinforcements 1. Numeral 6 designates the place, on beam 3, against which the wedgeshaped elongation 5 is driven. Numeral 7 is the end of the wedgeshaped elongation 5.

Reinforcements 1 may be of any suitable design. I attach, at the one end of reinforcements 1, hooks 2, which hold reinforcements 1 firmly to beams 3. Between beams 3, and under reinforcements 1, I place a horizontal form (not shown) upon which the fireproof infilling is laid. The fireproof infilling, together with the reinforcements 1, forms the floor, and beams 3 serve as supports for this floor, while columns 4, in turn, support beams 3.

After having described the above I am now coming to that which constitutes my invention, herein.

In order to stretch and interlock reinforcements 1 with beams 3, I add the wedgeshaped elongations 5, to reinforcements 1, at the opposite ends to hooks 2.

In Fig. 1 I have shown that the length of reinforcement 1 just allows end 7, of the wedgeshaped elongation 5, to clear beam 3 at 6. Due to the fact that the angle, between wedgeshaped elongation 5 and rein-

forcement 1, is not less than 90°, and that hook 2 is firm with the opposite beam 3, the wedgeshaped elongation 5 will, when driven, be wedged against 6, and consequently stretch and interlock reinforcement 1 with beams 3. If said angle had been less than 90°, reinforcement 1 would have dropped loosely on beam 3, after the end 7, of the wedgeshaped elongation 5, had passed 6.

Fig. 2 shows reinforcement 1, stretched and interlocked with beams 3, after the wedgeshaped elongation 5 is driven, and Fig. 3 gives a plan view of the reinforcements 1, in place, and ready to receive the infilling. When member 5 is driven the point 7 of 5 is bent in, thereby preventing 5 from slipping back.

I make reinforcement 1 a suitable fraction shorter than the distance between 6 and the point where hook 2 contacts beam 3. Reinforcement 1 may, thereby, be stretched the length of said fraction, when elongation 5 is driven against 6 of beam 3.

The simplicity of my invention facilitates a great saving in labor, as well as a saving in wedgeshaped material.

Other modifications of construction may be made without departing from the spirit of my invention.

I claim:—

1. In a reinforcement of an infilled structure spanning spaced flanged beams, the combination of means for attaching the one end of said reinforcement to a portion of one of said beams and the other end of said reinforcement bent to form a wedge-like member to engage the flange on the opposed beam, whereby said reinforcement is initially tensioned and wedged to said beams when said member is driven.

2. In a reinforcement of an infilled structure spanning spaced flanged beams, the combination of a hook at one end of said reinforcement engaging the flange of the one of said beams, and the other end of said reinforcement bent to form a wedge-like member to engage the flange of the opposed beam, whereby said reinforcement is initially tensioned and wedged to said beams when said member is driven.

HENRY SORENSEN.
